UNITED STATES PATENT OFFICE.

CHARLES H. HILL, OF SCHENECTADY, NEW YORK, ASSIGNOR TO GENERAL ELECTRIC COMPANY, A CORPORATION OF NEW YORK.

CALIBRATING DEVICE.

No. 861,212.

Specification of Letters Patent.

Patented July 22, 1907.

Application filed April 28, 1904. Serial No. 205,342.

To all whom it may concern:

Be it known that I, CHARLES H. HILL, a citizen of the United States, residing at Schenectady, county of Schenectady, State of New York, have invented certain new and useful Improvements in Calibrating Devices, of which the following is a specification.

My invention relates to calibrating devices for the operating magnets of circuit-breakers, relays and the like, in which the magnet is of the solenoid type and in which the various calibrations are obtained by adjusting the position of a stop against which the movable core or plunger of the solenoid is adapted to rest, and it comprises a novel construction and arrangement of parts for this purpose which will be best understood upon reference to the following detailed description taken in connection with the accompanying drawing.

Figure 1 of said drawing is a side elevation of a circuit-breaker provided with my invention; Fig. 2 is a vertical section of the calibrating tube illustrating the stop and its operating mechanism; and Fig. 3 is a section taken on the line 3-3 of Fig. 2.

Throughout these figures like characters refer to like parts.

The circuit-breaker which is here shown for the purpose of illustrating the application and use of my invention comprises contact studs 10 and 11 and a contact-carrying member 12. The upper contact stud 10 is provided with a brush 13 which extends downward and outward into position to be engaged by the contact 14. The contact 14 is included in circuit with a tripping coil 15 carried by the member 12 and connected at its lower end by a flexible connection 16 to the lower contact stud 11. Secondary contacts 17 and tertiary contacts 18 are carried by the contact stud 10 and the movable member 12, as illustrated. Contact is established by rocking the member 12 about its pivot 20 by means of the operating handle 21 which is pivoted at the point 22 to the member 12 and at the point 23 to a supporting link 24 which is pivoted to the upper end of the lower stud 11 which forms part of the carrying frame for the movable parts of the breaker. When the handle 21 is forced downward, the handle and the member 12 produce a toggle action to cramp the brush 13 and the contact 14 into close engagement. The latch 25 pivoted to the lower end of the member 12 engages a lug 26 to hold the breaker in its closed position. This latch may be tripped manually by pressing against the button 27 or electrically by the pin 28 carried by the core or plunger 29 engaging the inner end 30 of the latch. As soon as the latch is disengaged from the lug 26 the member 12 is drawn downward by the force of gravity and the breaker is opened.

The above circuit-breaker constitutes no part of my

invention and is herein disclosed merely for the purpose of illustrating its application. The core 29 of the solenoid 15 rests at its lower end against a stop 31 within the calibrating tube 32, the stop and tube being threaded so that when the stop is rotated it will be moved longitudinally of the tube.

For the purpose of rotating the stop, a square rod 33 loosely passes through a square opening 34 in said stop and extends throughout the length of the calibrating tube 32. To prevent the rod 33 from interfering with the movement of the core 29 into engagement with its stop the core is provided with a suitable opening 34 preferably of sufficient size to permit the rod 33 to be freely rotated without rotating the core. The lower end of the rod 33 is firmly secured to the head 35 which has a portion of its outer surface threaded at 36. This head terminates at its upper end in a collar 37 which rests against a shoulder 38 formed by the ring 39 at the lower end of the calibrating tube. By turning the milled portion of the head 35 in either direction, the stop 31 will be rotated and correspondingly moved longitudinally of the calibrating tube.

In order to set the stop for any desired calibration, a knurled nut 39a screwed upon the threaded portion 36 of the head 35 is turned firmly against the bottom of the tube so as to bring the collar 37 into close engagement with the shoulder 38, thus securely clamping the rod 33 and consequently the stop 31 in the desired position. The outer end of the pin 28 which passes through a slot 40 in the calibrating tube 32 is provided with a sharp edge 41 which serves as a pointer to indicate upon the scale 41a the calibration of the coil.

With the calibrating device which I have herein disclosed, it will be seen that the adjustment of the stop may be readily accomplished without the use of a screw-driver or other device, such as is now commonly necessary, and that the striking of the core 29 against the stop has practically no tendency to loosen the clamping nut 39 and thus change the calibration. This is the result of the loose connection between the stop 31 and the rod 33, by which the blow of the core 29 does not tend to move the rod 33 longitudinally but at most only tends to rotate the stop 31 and thus transmit a motion of rotation to said rod. This will not loosen the clamping nut 39; whereas it is found in practice that if the blow of the core 29 were transmitted directly to the rod 33 or its head 35, the clamping nut 39 would readily be loosened and the calibration of the device thereby altered.

It should also be noted that in the device which I have herein disclosed the operating rod 33 and its head 35 have a motion of rotation only and are not longitudinally movable in the calibrating tube 32, so that for all

calibrations the over-all dimension of the device remains unchanged.

What I claim as new and desire to secure by Letters Patent of the United States, is,—

- 5 1. The combination with a solenoid and its core, of a calibrating tube into which the core is adapted to pass, a stop rotatably mounted therein, coöperating means carried by said tube to cause longitudinal adjustment of the stop when rotated, and a rod for rotating said stop.
- 10 2. The combination with a solenoid and its core, of a calibrating tube into which the core is adapted to pass, a stop rotatably mounted therein, coöperating means carried by said tube to cause longitudinal adjustment of the stop when rotated, a rod for rotating said stop, and means for securing said rod against rotation.
- 15 3. The combination with a solenoid and its core, of a calibrating tube into which the core is adapted to pass, a stop rotatably mounted therein, coöperating means carried by said tube to cause longitudinal adjustment of the stop when rotated, a rod for rotating said stop extending lengthwise of said tube, and means located at the end of said tube for securing said rod against rotation.
- 20 4. The combination with a solenoid and its core, of a calibrating tube into which the core is adapted to pass, a stop rotatably mounted therein, coöperating means carried by said tube to cause longitudinal adjustment of the stop when rotated, a rod for rotating said stop, and means for clamping said rod to said tube.
- 25 5. The combination with a solenoid, of a centrally-aper-tured core therefor, a stop for said core rotatably movable for longitudinal adjustment, and a rod for rotating said stop extending through an opening therein and adapted to extend into the central aperture in said core.
- 30 6. The combination with a solenoid and its core, of a calibrating tube into which the core is adapted to pass, a stop rotatably mounted therein, coöperating means carried by said tube to cause longitudinal adjustment of the stop when rotated, a rod for rotating said stop, a calibrating head rotatably mounted at the outer end of said tube and secured to said rod, and a nut for clamping said head against said tube.
- 35 7. The combination with a solenoid and its core, of a stop therefor rotatably movable for longitudinal adjustment, means for rotating said stop having a loose connection therewith, and means for clamping said rotating means against rotation.
- 40 8. The combination with a solenoid and its core, of a stop for said core rotatably movable for longitudinal adjustment, an operating rod for said stop having a loose connection therewith, and means for clamping said rod against rotation.
- 45 9. The combination with a solenoid and its core, of a stop for said core rotatably movable for longitudinal adjustment and having a square opening therein, a square operating rod through said opening, and means for clamping said rod against rotation.
- 50 10. A calibrating device for an automatic circuit-breaker, having an adjustable stop to receive the impact of the core when released, and an adjusting device to regulate the stop independently supported so as to be practically free from such impact.

In witness whereof, I have hereunto set my hand this 27th day of April, 1904.

CHARLES H. HILL.
